UNITED STATES PATENT OFFICE.

GEORGE W. ELLIS, OF PHILADELPHIA, PENNSYLVANIA.

IMPROVEMENT IN TRUSSES.

Specification forming part of Letters Patent No. **222,579**, dated December 16, 1879; application filed October 31, 1879.

To all whom it may concern:

Be it known that I, GEORGE W. ELLIS, of the city and county of Philadelphia, and State of Pennsylvania, have invented a new and Improved Truss; and I do hereby declare that the following is a full, clear, and exact description of the same.

My invention is an improvement in the class of trusses for reducing hernia, in which the pad is attached to a slotted bar whose head is held in a clamp that allows adjustment of the pad in various positions.

My invention consists in constructing the bar to which the pad is attached with a ball for adjustment at its upper end and with an open slot, forming two parallel prongs, which enables the pad to be attached or detached with great facility.

This construction of the bar C with an open slot or parallel prongs enables the pad A to be readily detached from the bar and another substituted, which is particularly important in fitting trusses, since it often happens that the pad attached to a truss is uncomfortable or otherwise unsuitable to the wearer, and in such case the pad may be removed and another or others applied without necessitating removing the whole truss.

In accompanying drawings, forming part of this specification, Figure 1 is a front view of a truss provided with my improvements. Fig. 2 is an edge view, partly in section, of the clamp for holding the bar to which the pad is attached. Fig. 3 is a cross-section on line *xx*, Fig. 1.

The pad A is attached to the spring B by means of a sliding or adjustable bar, C, having an open slot, *a*, in one end, and a ball or spherical protuberance, *b*, on the other, which is secured in a clamp, D.

The details of construction, arrangement, and operation of said parts are as follows: The pad A is provided with a fixed T-shaped stud, *c*, and a detachable clamp-screw, *d*. The slotted bar C is secured to the pad A by sliding its parallel prongs under the flanges of the stud *c* and the head of clamp-screw *d*, which latter is then tightly screwed down on the bar to hold it firmly.

The clamp D consists of the recessed plate *e*, which is fixedly attached to the spring of the truss and a movable or detachable plate, *f*, which is adapted to partly embrace the ball *b*, and is provided with teeth to enable it to hold the pronged bar C immovable in any position. Said plate *f* is secured by a clamp-screw, *g*.

What I claim is—

In a truss, the bar constructed with an open slot or parallel prongs and a spherical head integral therewith, as shown and described, to adapt it to use with a pad and with the clamp of the body-band, as specified.

GEORGE W. ELLIS.
